[57] ABSTRACT

A mass of seafood chunks is placed on a chute having a reciprocating spreader which spreads the mass on the chute and hooks on a drum are moved through the lower edge of the mass to hook individual chunks and then drop the chunks onto a conveyor, a rotary brush assisting to strip the chunks from the hooks.

SEAFOOD SORTER

DETAILED DESCRIPTION

This invention relates to a seafood sorter and more particularly to a sorter for separating wet, sticky chunks of seafood from a pile of such chunks.

An object of the invention is to provide a seafood sorter.

Another object of the invention is to provide a sorter for separating wet, sticky chunks of seafood from a pile of such chunks.

A further object of the invention is to provide a sorter adapted to hook into individual seafood chunks and separate them from a pile of such chunks.

Another object of the invention is to provide a sorter having a drum with peripheral hooks having tong portions which are generally parallel to the periphery of the drum, are spaced from the drum a distance less than the thickness of a seafood chunk to be separated from a mass of such chunks and are of a length less than the thickness of the chunks.

Another object of the invention is to provide an apparatus for pulling wet, sticky seafood chunks one at a time from a mass of such chunks.

The invention provides a seafood sorter including hook-like impaling members each adapted to hook into an edge portion of a wet, sticky seafood chunk such as, for example, a shrimp or an oyster, of a pile of such chunks and pull the chunks from the pile. Preferably, each impaling member has a tine portion carried by a drum in a position parallel to the periphery of the drum, of a length less than the average thickness of the seafood chunks to be separated and spaced from the drum a distance less than that thickness.

In the drawings:

FIG. 1 is a fragmentary vertical sectional view of a seafood sorter forming one embodiment of the invention;

FIG. 2 is a fragmentary top plan view of the seafood sorter of FIG. 1;

FIG. 3 is an enlarged fragmentary view taken along line 3—3 of FIG. 1; and

FIG. 4 is an enlarged fragmentary vertical sectional view taken along line 4—4 of FIG. 2.

Referring now in detail to the drawings, there is shown therein a seafood sorter forming one embodiment of the invention and including a chute 10 on which are placed seafood chunks 12, which may be whole, peeled shrimp, shucked oysters, fish fillets or the like. A separating drum 14 having hooks 16 rotates and each hook hooks into one of the chunks and carries it over the top of the drum and past a brush 18 and drops it on a belt-type conveyor 20. A spreader comb 22 is reciprocated slowly on the chute 10 by a fluid pressure cylinder drive 24 to spread the pile of chunks over the entire width of the chute between sides 26 of the chute. Teeth or fingers 28 of the comb 22 are narrower than support fingers 30 of the chute and reciprocate between the edges of the fingers 30, the fingers 30 being positioned on opposite sides of slots 32 providing clearance for the hooks 16.

The hooks 16 have very sharp points 40 and top sharpening flats 42 which are concentric to axle portion 44 of the drum to permit sharpening of the points 40 by turning the drum and holding an abrading member so that it is engaged by the flats as the latter are moved

past the abrading member. The hooks have circumferentially impaling portions substantially concentric to the periphery of the drum 46 and also have substantially radial shank portions 48 and roughened anchor portions 50 secured in holes 52 by cast epoxy resin anchor portions 54. For best results the shank portions are of a length such that the impaling portions are about five-sixteenths inch which is slightly less than the average thickness of the portions of the chunks which are impaled, from the periphery of the drum and the distance from the points 40 of each hook is about one-half inch which is slightly less than the average thickness of the portions of the chunks which are impaled from the projected centerline of the shank portion 50. The hooks, the drum, the chute and the comb preferably are of stainless steel, and the bristles of the brush are preferably of highly smooth plastic material such as, for example, nylon.

The axle portion 44 (FIGS. 1 and 2) is journaled in bearings 60 carried by frame 62, and an axle 64 of the brush 18 is journaled in bearings 66 carried by the frame 62. Chain and sprocket drives 68 and 70 drive the drum and the brush in inrunning directions and at speeds such that the outer circumference of the brush is faster than the hooks so that the brush strips the chunks 12 off the hooks and drops the chunks onto the conveyor 20. The hooks are so staggered and the speeds of the conveyor and the drum are such that the chunks drop individually onto clear spaces on the conveyor. That is, the chunks on the conveyor are spaced from each other. The conveyor conveys the separated chunks to cryogenic freezing apparatus where the moist chunks are individually frozen.

The periphery of the drum 14 is smooth so that the wet, sticky chunks 12 will slide thereon, and the weight of the chunks is enough to prevent the drum by itself, without the hooks 16, from lifting the chunks up around the drum. The hooks embed themselves in the individual chunks and pull the chunks out individually from the pile or mass. The hooks, because of their spacing from the drum and the length of the impaling portions, are each usually fully embedded in a single one of the chunks. The chute, with the comb, feeds the pile of chunks in a spread out condition to the bite of the chute and the lower right-hand portion of the drum.

What is claimed is:

1. In a seafood sorter,
support means for supporting a pile of seafood chunks,
hook means,

carrier means comprising a rotary drum for moving the hook means through the pile to impale one of the chunks and pull that chunk from the pile,
the drum being rotatable on a horizontal axis and the support means comprising a feed chute forming an acute angle with the lower side of the drum,
the carrier means including means for rotating the drum in a direction in which the hook means is moved upwardly past the feed chute,
and a spreader member adapted to spread the pile over the portion of the chute adjacent the drum.

2. The seafood sorter of claim 1 wherein the chute has clearance slots to permit passage of the hook means therethrough and the spreader member is comb-like with teeth movable over the portions of the chute between the slots.

3. In a seafood sorter,
support means for supporting a pile of seafood
chunks,
an elongated drum mounted for rotation on a
horizontal axis,
a plurality of hooks mounted on and spaced along
and around the drum,
means for rotating the drum to move the hooks

through the pile to impale one of the chunks and
pull that chunk from the pile,
means for spreading the chunks in the pile,
conveyor means,
and stripper means for moving the chunks from the
hooks onto the conveyor means after the chunk
has been pulled from the pile.
